UNITED STATES PATENT OFFICE.

WILLIAM S. GRAFTON, OF STEUBENVILLE, OHIO, AND EDWIN C. EWING AND ALEXANDER GLASS, OF WHEELING, WEST VIRGINIA, ASSIGNORS TO THE WHEELING CORRUGATING COMPANY, OF WHEELING, WEST VIRGINIA.

DESIGN FOR A CEILING-PLATE.

SPECIFICATION forming part of Design No. 22,273, dated March 7, 1893.

Application filed February 4, 1893. Serial No. 461,219. Term of patent 14 years.

To all whom it may concern:

Be it known that we, WILLIAM S. GRAFTON, residing at Steubenville, in the county of Jefferson and State of Ohio, and EDWIN C. EWING and ALEXANDER GLASS, residing at Wheeling, in the county of Ohio and State of West Virginia, citizens of the United States, have invented and produced a new and original Design for Metallic Finishing-Plates for Buildings, of which the following is a specification, reference being had to the accompanying drawing, forming part hereof, which shows a metallic finishing-plate or ceiling-plate designed according to our invention.

Our design consists of a square or rectangular metallic finishing plate A, divided into equal parts or sub-divisions B, by ribs or projections *a a'*, extending from one side of the plate to the other, and crossing each other at right angles. Each of the sub-divisions B, is further sub-divided by means of ribs or projections *c*, crossing each other at the center

of the sub-division B, and connecting the diagonally opposite angles thereof. At each intersection of the ribs or ridges *a a'*, there is formed a circular projection C.

The essential feature of our design is a metallic finishing plate divided by ribs or ridges, crossing each other, and each sub-division containing ribs or ridges crossing each other at the center of the sub-division, and connecting the diagonally opposite angles thereof.

We claim—

The design for a metallic finishing plate herein shown and described. 35

In testimony whereof we have hereunto subscribed our names.

WILLIAM S. GRAFTON.
EDWIN C. EWING.
ALEXANDER GLASS.
